UNITED STATES PATENT OFFICE.

ALBERT R. GARDNER, OF ST. LOUIS, MISSOURI, ASSIGNOR OF ONE-FOURTH TO J. C. JOSSE AND ONE-FOURTH TO F. R. LOVERIDGE, BOTH OF ST. LOUIS, MISSOURI.

SAFETY ELECTRIC SWITCH.

1,402,157.

Specification of Letters Patent. Patented Jan. 3, 1922.

Application filed April 23, 1920. Serial No. 376,016.

To all whom it may concern:

Be it known that I, ALBERT R. GARDNER, a citizen of the United States, and resident of St. Louis, Missouri, have invented certain new and useful Improvements in a Safety Electric Switch, of which the following is a specification.

This invention relates to improvements in a safety electric switch, the same being of the knife switch type all encased within a housing and operated by a handle on the outside of the housing with a means attached for operating the switch and converting it into a snap switch type.

15 A further object of my invention is to construct a switch which is to be manipulated so as to make and break the contact with a snap so as to prevent arcing and thereby binding the contact points with which the blade of the switch communicates.

20 A further object is to construct the switch with an intermediate mechanism which will make and break the contact with a jerk or snap without in any way causing injury to 25 the hands of the operator when manipulating said switch.

The entire mechanism with the exception of the operating handle being encased in the housing so as to make the switch absolutely 30 safe to the operator.

Figure 1, is a side view of my invention.

Fig. 2, is a top plan view with the cover of the housing removed.

Fig. 3, is a central sectional view of the 35 same.

Fig. 4, is a central horizontal sectional view.

Fig. 5, is a detail sectional view showing 40 the intermediate operating mechanism for manipulating the knife switch and showing the same in closed position.

Fig. 6, is a similar view to Fig. 5 but showing the contact broken.

Fig. 7, is a detail sectional view of a portion 45 of the operating mechanism for manipulating the intermediate mechanism.

Fig. 8, is a detail sectional view of a portion 50 of the operating mechanism showing the means for removing the sudden jerk from the handle.

Fig. 9, is a detail perspective view of the sleeve to which the operating handle is attached.

In the general construction of my invention I provide a suitable housing or other

casing consisting of a bottom 10, side walls 11 and 12 and end walls 13. To one of the side walls is hingedly mounted a cover 14 by which the entire interior mechanism is concealed from view.

60 In this housing or casing is mounted my improved switch which consists of an insulated base-plate 14' securely fastened to the bottom of the housing and on this base plate is mounted contact points 15 and the knife 65 switch supporting members 16 which are in the form of eared members firmly secured to the base and between the same are hingedly supported the contact blades or knife switches 17.

70 On the base plate is likewise provided fuse supporting clips 18 in which are supported the fuses of the standard type.

In this particular illustration which comprises my invention I show a switch constructed of three contacts thereby providing the blades or knife switches 17 which are connected together by a cross bar or rod 19 and held thereto by the clamps 20.

75 By means of this cross bar all of the blades are simultaneously operated and this bar is connected to a crank arm lever 21 by means of the connecting links 22, the crank arm has suitable bearing in the housing, its one end having bearing in the wall 12 at 85 the point indicated by the numeral 23, the other end extending into a cylindrical extension 24 forming a part of a disc 25. A portion of the periphery of this disc being provided with gear teeth 26 and these teeth 90 in turn are arranged in mesh with gear teeth 27 formed on a corresponding disc 28 axially mounted on the wall 11 of the housing.

To the disc 28 is pivotally attached a 95 swivel link 29 to which is attached a spring 30, the other end of the spring attached to an adjusting hook 31, the position of the link is such as to cause the discs to be operated by means of pressure being exerted 100 thereon by the springs 30, either in one or the other direction so as to operate the switch with a sudden jerk or snap at a time when the link reaches a point over the center of the axis on which the disc 28 is 105 mounted.

On the disc 25 is firmly attached a yoke 32, this yoke straddles the vertical portion 33 of the crank arm and the same is of such length as to permit the crank arm to op- 110

erate freely until one or the other horizontal portions 34 of the yoke is brought in contact with the crank arm, at the same time the discs are rotating and just as soon as the pivot point of the link 29 passes the center of the axis on which the disc 28 is mounted it will cause the discs to operate with a snap thereby throwing the knife switches or contact blades in or out of contact with a quick and rapid snap.

During this operation in order to avoid sudden action from jerking the hand of the operator when manipulating the switch by means of the handle 33', I attach the handle 33' in the sleeve 34', this sleeve is slipped over the cylindrical projection 24 and the same is held in position thereon by means of a key 35 passing diagonally through the sleeve and extending into a groove 36 formed in the projection 24, this permits movement of the sleeve on the projection yet holds the same from being pulled off, and in order to provide for the snap operation and to relieve the jerk from the hand, the sleeve 25 is provided with a recess 37 in which is inserted a key 38 mounted on the projection 24. This recess is of sufficient width as to allow movement of the key when the spring pressure creates its action on the discs.

In Figs. 6 and 7 I show positions the switch assumes, in Fig. 6, the contact is broken and the yoke 32 is in contact with the portion 33 of the crank arm but when it is desired to close the switch the discs are 35 permitted to rotate without manipulating the switch until the yoke 32 comes in a position as shown by dotted lines 39 shown in Fig. 6; then the switch is gradually moving forward to a closed position until the link 40 29 raises slightly above the center of the axis and then by the pulling of the spring the blades are swiftly inserted between the contact points 15 without in any way causing an arc.

When opening the switch from the position as that shown in Fig. 5 which shows closed in solid lines and open in dots, the handle 33' is pulled upon until the opposite side of the yoke 32 contacts with the crank arm, then by continuing forward a slight distance the pressure of the spring will rotate the discs, throwing the switch open with a sudden snap.

The essential feature of my invention is to attach to a switch of this type a pair of discs having a portion of their periphery provided with gear teeth with such number

and size as to operate the switch under spring pressure to cause the switch to open and close instantly and the movement is limited by means of contact of the undisturbed or un-toothed portion of the periphery of the discs as that indicated by the numeral 40.

Having fully described my invention what I claim is:

1. A switch of the character described comprising a housing, a crank shaft supported therein, a base plate mounted in the housing a plurality of contact blades hingedly mounted to the base plate, a connecting arm having connection with the contact blades, a pair of links connecting the crank arm to the connecting rod, a pair of discs axially mounted to the side of the housing, the one end of the crank arms passing centrally through one of said discs, a spring communicating with the other of said discs having a portion of their periphery provided with meshing gear teeth, a yoke formed on one of the discs and straddling the crank arm; a sleeve connected to one of said discs the same having suitable play so as to relieve a jerk to the hand of the operator, and a handle connected to the sleeve for operating the discs to throw the switch in and out of contact, substantially as specified.

2. A switch of the character described comprising a pair of axially mounted discs, a portion of the periphery of each being provided with meshing gear teeth, a spring attached to one of the discs for operating the same when the disc is turned past center, a trunnion formed on one of the discs and extending outwardly, a sleeve located on said trunnion, a key formed in the trunnion which operates in a recess formed in the sleeve, a handle formed on the sleeve for manipulating the trunnion, a crank shaft connected to one of said discs, a yoke formed on said disc and straddling the crank shaft and by which the crank shaft is thrown either to the right or left in combination with a plurality of contact blades manipulated by the crank arm, substantially as specified.

In testimony whereof, I have signed my name to this specification, in presence of two subscribing witnesses.

ALBERT R. GARDNER.
